UNITED STATES PATENT OFFICE.

JOHN W. BAIRD, OF CHICAGO, ILLINOIS.

SPARK-PLUG.

1,206,794.

Specification of Letters Patent. Patented Dec. 5, 1916.

Application filed October 23, 1915. Serial No. 57,460.

To all whom it may concern:

Be it known that I, JOHN W. BAIRD, a citizen of the United States, and a resident of the city of Chicago, county of Cook, and 5 State of Illinois, have invented certain new and useful Improvements in Spark-Plugs, of which the following is a specification.

My invention relates to improvements in spark plugs for explosion engines, and has 10 for its object the production of a spark plug which, when in use, will not readily foul.

A further object is the production of a spark plug as mentioned, which will be of simple construction and efficient in use.

15 Other objects will appear hereinafter.

With these objects in view, the invention consists in the combinations and arrangements of parts hereinafter described and claimed.

20 The invention will be best understood by reference to the accompanying drawing forming a part of this specification, and in which,

Figure 1 is a central longitudinal section 25 of a spark plug embodying the invention, Fig. 2 is a bottom plan view thereof, Fig. 3 is a central longitudinal section through the lower portion of a spark plug of a slightly modified form, Fig. 4 is a central 30 longitudinal section through the lower portion of a spark plug of still another form, and Fig. 5 is a bottom plan view of the construction shown in Fig. 4.

The preferred form of construction, as 35 illustrated in the drawing, is embodied in a spark plug which in the main is of conventional construction, comprising an outer tubular body 1 which forms one pole of the plug and an inner slender rod 2 which forms 40 the other pole of the plug, the parts 1 and 2 being connected together and insulated from each other in the usual manner, the arrangement being such as to result in the formation of an annular inwardly opening 45 space A between the inner end portions of said parts.

The novelty of the present invention is 50 embodied in a fan or propeller wheel 3 which is mounted upon the reduced lower end of the member 2, the latter being formed with an annular shoulder 4 to prevent longitudinal movement of the wheel 3 thereon in one direction. Said fan wheel is locked in position by upsetting the end 5 of the 55 member 2, a washer 6 being inserted between said upset end and the fan wheel in order

to alleviate friction. In order to insure against binding of the fan wheel upon the member 2, said fan wheel is formed with an elongated hub 7, as clearly shown. 60

The blades or vanes of the wheel 3 are of usual design, the same radiating from the hub 7 and being transversely bent or inclined so that upon a current of air contacting therewith the fan wheel will be rotated. 65

In the use of the spark plug the blades of the fan wheel constitute the points of the inner pole member 2, the spark being jumped from said points through the space 70 intervening the same and the adjacent lower or inner edge of member 1. The arrangement is such that in the exhaust of the spent gases from the combustion chamber of the engine, said gases, in rushing past the spark 75 plug toward the exhaust port, will impinge upon the blades of the fan wheel and thus cause rotation of the latter. Such rotation of said fan wheel will serve to dislodge any carbon, soot or other foreign matter which 80 may have been deposited thereon during the explosion, and hence, with this arrangement, upon each discharge of spent gases from the engine, the points of the spark plug will be 85 automatically cleaned. The rotation of said 90 fan wheel also results in the creation of eddies or currents around the lower end of the part 2 and in the space A which further insures against the deposit of any appreciable amount of soot, carbon or foreign matter 95 upon the lower end of member 1 or the walls of space A.

In the form shown in Fig. 3, an annular extension member 8 is provided having pins 9 which engage with recesses 10 formed 95 in the adjacent end of part 1, the arrangement being such as to result in the formation of an annular space 11 at the inner end of member 1. In this arrangement, during rotation of the fan wheel, as just described, air currents will be created which will cause a draft or outward movement of air and gases through the space 11. The outward rushing or movement of air or gases through said space will also have the 100 effect of creating a suction in the upper portion of space A and thus serve, it is thought, to more effectually agitate the air and gases in this space and with the necessary result of insuring dislodging and removal of foreign matter therefrom. 110

In the form shown in Figs. 4 and 5, an

oscillatory bar 12 is employed pivotally mounted for oscillation about a transverse axis at the inner end of pole member 2'. The pivotal pin 13 which connects the bar 12 with the pole member 2' passes through ears 14 provided at opposite sides of said bar, the corresponding sides of said pole member being flattened in order to afford engagement for said ears, as will be readily understood. Said bar 12 is permitted free oscillatory movement within a fixed range, the movement thus afforded being determined by the corners 15 at the lower end of pole piece 2' which are adapted for engagement against the upper side of the bar 12 in order to limit pivotal movement thereof, as shown in dotted lines in Fig. 4. The arrangement is such that the member 12 will be prevented from contacting with the member 1 of the spark plug, a gap being always formed between the ends of said bar and the lower or inner edge of the member 1 for the jumping of the spark.

With the latter construction, it will be seen that during explosion in the engine cylinder or upon the rushing of gases from the cylinder during scavenging of the latter, the disturbance of the air and gases within the cylinder will have the effect of vibrating the member 12 so as to shake any soot, carbon or other foreign matter therefrom in order to prevent fouling in the operation of the spark plug.

While I have illustrated and described the preferred forms of construction for carrying my invention into effect, these are capable of variation and modification without departing from the spirit of the invention. I, therefore, do not wish to be limited to the precise details of construction set forth, but desire to avail myself of such variations and modifications as come within the scope of the appended claims.

Having described my invention what I

claim as new and desire to secure by Letters Patent is:

1. A spark plug for explosive engines comprising an outer tubular body forming one pole of the plug; an inner concentric longitudinally extending member arranged in said body and forming the other pole of the plug, there being an annular space formed between the inner end portions of said body and member; and a fan wheel mounted for free rotary movement on the inner end of said member and adapted, when rotated, to force a current of air or gases into said space, there being a laterally opening continuously open passage provided in said body leading from said space and adapted to communicate with the combustion chamber in conjunction with which the plug is used, substantially as described.

2. A spark plug for explosive engines comprising an outer tubular body forming one pole of the plug; an inner concentric longitudinally extending member arranged in said body and forming the other pole of the plug, there being an annular space formed between the inner end portions of said body and member; and a fan wheel mounted for free rotary movement on the inner end of said member and adapted, when rotated, to force a current of air or gases into said space, there being an annular laterally opening continuously open passage provided in the inner portion of said body leading from said space adapted to communicate with the combustion chamber in conjunction with which the plug is used, substantially as described.

In testimony whereof I have signed my name to this specification in the presence of two subscribing witnesses.

JOHN W. BAIRD.
